[57] CLAIM

The ornamental design for a leash holder, as shown and described.

DESCRIPTION

FIG. 1 is a top, front, and right side perspective view of a leash holder showing our new design, the partial broken-like disclosure of a leash being for illustrative purposes only and forming no part of the claimed design; FIG. 2 is a right side elevational view thereof, the left side being a mirror image of that shown; FIG. 3 is a front elevational view thereof; FIG. 4 is a rear elevational view thereof; FIG. 5 is a bottom plan view thereof; and, FIG. 6 is a top plan view thereof.

FIG. 1

FIG. 2

FIG. 3

FIG. 4

FIG. 5

FIG. 6
